HANDLE FOR ELECTRICAL CONNECTORS

Herbert Hamilton Andersen, Jr., 140 Highplain Road,
Andover, Mass. 01810, and Stephen Anthony Mach-
cinski III, 19 Seymour St., Winthrop, Mass. 02152

Filed Dec. 19, 1974, Ser. No. 534,549

Term of patent 14 years

Int. Cl. D7—02; D8—07; D13—03
U.S. Cl. D26—1 R

Fig. 2.

Fig. 4.

Fig. 5

Fig. 6.

FIG. 1 is a perspective view of a handle for electrical connectors showing our new design, the connector being shown in broken lines for illustrative purposes only;

FIG. 2 is a view in side elevation of the handle;

FIG. 3 is a view in front elevation of the handle;

FIG. 4 is a view in rear elevation of the handle;

FIG. 5 is a plan view of the handle; and

FIG. 6 is a bottom view of the handle.

We claim:

The ornamental design for a handle for electrical connectors, as shown and described.
